INVENTOR,

Homer D. Tracy,

BY

John Edward
ATTORNEY

UNITED STATES PATENT OFFICE

HOMER D. TRACY, OF RIDGEWOOD, NEW JERSEY

BLADE SHARPENER AND THE LIKE

Application filed January 18, 1930. Serial No. 421,717.

This invention relates to means for operating on articles by attrition, as on razor blades, and especially those of the flat type, such as Gillette razor blades, to polish and refine or recondition them and their cutting edges, and its object is to provide means of this class which shall be simple and compact in construction and inexpensive to manufacture. The invention distinguishes from known means of this class in this respect: Given a pair of members adapted to clamp between them the article to be subjected to attrition and one of which is rotatively or otherwise slidably relatively to the other on the interposed article, that one member (at least) has its article-clamping surface an attrition surface and that the article-clamping surface of each member opposes substantially the same degree of resistance as the other member to sliding of the article between them; in the example herein set forth both members have their clamping surfaces attrition surfaces of substantially equal frictional value and thus oppose substantially equal resistance to the sliding of the article between them. The invention also distinguishes from known means of this class in this respect: Given a pair of members adapted to clamp between them the article to be subjected to attrition and one of which is rotative relatively to the other around an axis penetrating them, that each member has its article-clamping surface an attrition surface and that one of said members has means coactive with the interposed article to confine it and the article to relative rotary motion around an axis penetrating them; in the said example said means is also coactive with the other member to confine the two members and article to relative rotary motion around said axis. The invention also distinguishes from known means of this class in this respect: Given a pair of clamping members adapted to clamp between them the article to be subjected to attrition and one of which is rotatively or otherwise slidably on the clamping surface of the other, that the clamping surface of one is yieldable to the article and that the clamping surface of the other is an attrition surface;

in the said example the clamping surfaces of both members are yielding and attrition surfaces, whereby the attrition action will be effective on both bevels (on opposite faces) at the edge of a razor blade.

In the said example the improved means is assumed to be utilized in the polishing and reconditioning or refining of the edges of razor blades of the Gillette type and by a simple manual operation.

In the drawing;

Fig. 1 shows one member of my means held in one hand of the operator with the blade therein and the other about to be placed in clamping relation to the first member;

Fig. 2 illustrates the manner in which the said means is operated; and

Fig. 3 is a transverse sectional view of the said means and interposed blade.

1 designates the conventional Gillette safety razor blade having the central hole 2 for the central threaded stem of one clamping member of the razor frame and the holes 3 for the lateral studs of said member and having its parallel sides 4 beveled on the opposite faces of the blade to a cutting edge.

The two members of my means are counterparts of each other in these respects: Each is here shown of general disk-like form having a diameter at least as great as the length of the blade; and each comprises a metal or other stiff back 5 and a layer or pad 6 secured thereto in any way (as by cementing it thereto), the exposed surface 6a of said layer forming its clamping and attrition surface. The layer 6 is here of yielding flexible material, as leather, and it may be treated, if desired, as razor strops are treated, to increase or improve its attritive action. Each layer 6 is here of such nature as to oppose substantially the same degree of resistance as the other to sliding of the blade 1 in contact with it. The two members have coacting means for centering them with relation to each other and the interposed blade, as a stem 7 on the back 5 of one protruding through the layer 6 thereof and adapted to be received in the hole 8 of the other, extending through the hole 2 of the blade. Protuberances 9 are formed to pro-

ject from the exposed face of each back 6 to afford grips.

In treating the blade it is placed on one member as shown in Fig. 1 (as on the one 5 having stem 7, with said stem penetrating its hole 2) and then the other member is placed on the first so that the blade remains interposed. Then, holding the two members between the hands and in clamping relation 10 to the blade, the said members, by rotating one hand back and forth or the two hands in opposite directions and back and forth around stem 7 as an axis, are made to undergo relative rotation: See Fig. 2, where 15 the two members appear in dotted circular outline at A. The clamping action should be sufficient to embed the blade for one-half of its thickness in each (yielding) layer 6, thereby to bring the attrition action into effect 20 on the extreme edge at each side 4 of the blade, as shown by Fig. 3, if the object is to refine the edges as well as polish or otherwise treat the blade itself. The protuberances 9 embed themselves in the operator's 25 hands and thereby afford the required grip of the hands on the members.

Having thus fully described my invention what I claim is:

1. A device for sharpening the edge of a 30 flat blade comprising a pair of members adapted to clamp between them the blade to be sharpened and one of which is slidable on the clamping surface of the other, each member having its clamping surface an attrition 35 surface and yieldable to the interposed blade.

2. In combination, a pair of members adapted to clamp between them the article to be subjected to attrition and each comprising 40 a yielding pad affording an attrition surface and a stiff back therefor, and one being rotative relatively to the other on an axis penetrating them, said members having means, adapted to penetrate the interposed article, to confine said members against displacement relatively to each other radially of said axis.

3. A device for sharpening the edge of a flat blade comprising a pair of members 50 adapted to clamp between them the blade to be sharpened and one of which is slidable on the clamping surface of the other, each member comprising a yielding pad forming its clamping surface and a stiff back therefor.

55 In testimony whereof I affix my signature.
HOMER D. TRACY.
